United States Patent Office

Des. 181,439
Patented Nov. 12, 1957

181,439

WIRE STRINGER

Gerald A. M. Petersen, Santa Clara, Calif.
Application May 3, 1956, Serial No. 41,326

Term of patent 14 years
(Cl. D41—1)

Fig. 1 is a plan view of a wire stringer showing my new design therefor.

Fig. 2 is a side view of Fig. 1; and

Fig. 3 is a perspective view.

I claim:

The ornamental design for a wire stringer, as shown.
